Worcester, Mass., assignors to Worcester
Pressed Aluminum Company, Worcester, Mass.,
a corporation of Massachusetts

Application December 20, 1937, Serial No. 180,767

14 Claims.

(Cl. 164—69)

This invention relates to machines for trimming irregular edges at the open ends of metal cans and boxes, such irregular edges being practically unavoidable when boxes are formed from sheet metal blanks by pressing or drawing operations. While our improved machine is adapted for trimming all kinds of metal boxes, it is particularly designed for trimming boxes of non-circular cross section, such as square or rectangular boxes, and said machine demonstrates important advantages when so used.

It is the general object of our invention to provide a trimming machine which will quickly and easily trim off irregular edges at the open ends of metal boxes, and which will leave a smooth end, substantially without burrs.

Our invention further relates to arrangements and combinations of parts which will be herein-after described and more particularly pointed out in the appended claims.

A preferred form of the invention is shown in the drawings, in which

Fig. 1 is a side elevation of our improved trimming machine;

Fig. 2 is a partial plan view, partly in section and looking in the direction of the arrow 2 in Fig. 1;

Fig. 3 is a partial end view, looking in the direction of the arrow 3 in Fig. 1;

Fig. 4 is a partial plan view, looking in the direction of the arrow 4 in Fig. 1 and showing also a box on the mandrel, partly in section;

Fig. 5 is an enlarged end view of the cutter and die, looking in the direction of the arrow 5 in Fig. 4;

Fig. 6 is a fragmentary view showing the cooperating cutter and die in a different cutting relation;

Fig. 7 is a partial end view showing the operation of the scrap cutter;

Fig. 8 is a partial plan view of the mandrel and associated parts in spaced relation;

Fig. 9 is an end view of the scrap cutter, looking in the direction of the arrow 9 in Fig. 8;

Fig. 10 is an elevation of the die which is associated with the mandrel, looking in the direction of the arrow 10 in Fig. 8;

Fig. 11 is a sectional plan view of the mandrel and associated parts; and

Fig. 12 is a perspective view of a box after the trimming operation has been performed thereon.

Referring to Fig. 1, we have shown our improved machine assembled on a table 15 supported by legs or frame members 16. A cutter shaft 17 is mounted in bearing brackets 18 and 19 on the

table 15 and is aligned with a driving shaft 20, supported in a bearing 21 and connected to the shaft 17 by a one-revolution clutch 22. This clutch may be of any usual type and is conveniently operated by a foot lever 23 through a link 24. The shaft 20 is continuously rotated in any convenient manner as by a pulley 25 and belt 26.

A cutter 30 (Figs. 2, 3 and 5) is mounted on a disc 31 and may be secured thereto by screws 33. A plate 34 is pivoted on a pin 35 in the cutter 30 and may be swung to one side to give access to the screws 33. The disc 31, cutter 30 and plate 34 are all mounted on the front end of the cutter shaft 17 and are firmly secured to rotate therewith by a clamping screw 36 and a key 37 (Fig. 4).

A mandrel shaft 40 (Fig. 2) is mounted to rotate in the bearing bracket 18 and is driven from the cutter shaft 17 by a gear 41 and pinion 42 in a 2-to-1 ratio, so that the mandrel shaft 40 rotates twice for each single revolution of the cutter shaft 17.

A chip cutter 45, a die 46 and a mandrel 47 are assembled on the mandrel shaft 40, as shown in Fig. 11, and are secured in assembled relation thereon by a clamping screw 48.

These parts as illustrated are for a box of square cross section and with rounded corners, but it will be understood that the mandrel and associated parts may be made of any desired shape to fit any particular type and size of box to be trimmed.

The mandrel 47 is preferably provided with longitudinal grooves 49 (Figs. 3 and 4) which prevent the trapping of air between the closed end of the box and the outer end of the mandrel, which might otherwise be troublesome, due to the sealing effect of the lubricant used on parts associated with the mandrel.

The die 46 is a hardened steel plate and corresponds in outline to the cross section of the box to be trimmed, which box is a close sliding fit over the mandrel.

The chip cutter 45 is slightly smaller than the cutter 46 and is provided with sharp cutting members 50 at several of its corners, which cutting members closely engage a concentric portion 51 of the flanged disc 31 during the second or non-cutting revolution of the mandrel.

The chip cutter 45 is keyed to the mandrel 50 shaft 40, as indicated at 52 in Fig. 11, and is provided with a pin 53 (Fig. 8) extending through a hole 54 (Fig. 10) in the die 46 and into a hole 55 (Fig. 8) in the mandrel 47. With this construction, the parts 45, 46 and 47 rotate together 55

and are positively driven by the mandrel shaft 40. A chute 60 may be provided for conveying the scrap to a suitable receptacle.

Having described the details of construction of our improved trimming machine, the method of operation thereof is as follows:—

A box B is slipped over the mandrel 47 and die 46 to the position shown in Fig. 4, such action being permitted by a recessed portion 62 (Fig. 5)

10 in the cutter 30. When the parts are brought to rest by the operation of the one-revolution clutch, the recessed portion 62 is associated with the mandrel 47 in such manner that a box may be freely slipped on the mandrel.

15 After the box has been thus positioned, the foot lever 23 is depressed and the cutter shaft 17 makes one revolution, while the mandrel 47 and associated parts make two revolutions. During the first revolution of the mandrel, the irregularly 20 formed cutting edge 63 of the cutter 30 cooperates with the die 46 as shown in Figs. 4, 5 and 6 to trim the waste metal or scrap 65 (Fig. 4) from the open end of the box.

It will be noted that the cutting edge 63 is so 25 designed that the overlap between the edge 63 and the edge of the die 46 is substantially constant, regardless of the non-circular section of the die 46. A uniform cutting action thus takes place entirely around the box B, the scrap 65 being severed from the box as indicated in Fig. 30 4, and the end of the box being left with a smooth trimmed edge substantially devoid of burrs.

Having severed the ring of scrap 65 from the end of the box B, it is obvious that the scrap ring 35 must be removed before another box can be placed on the mandrel. For this purpose we provide the scrap cutter 45, which cooperates as indicated in Fig. 7 with the concentric flange 51 of the disc 31 during the second or non-cutting revolution of the mandrel shaft 40. During 40 this second revolution, the three sharp edge members 50 of the scrap cutter 45 engage the concentric flange 51 and sever the scrap ring 65 at three successive points. The severed pieces of 45 scrap then fall freely to the chute 60 by which they are conveyed away.

Having completed the second revolution of the mandrel shaft 40, the machine is brought to rest by the automatic action of the one-revolution 50 clutch 22, whereupon the trimmed box may be removed and an untrimmed box substituted therefor. The entire trimming and scrap-disposal operation is thus quickly and easily performed and the ends of the trimmed boxes are 55 smooth and uniform and in condition for immediate use.

Our improved machine is particularly adapted for trimming boxes pressed or drawn from aluminum or other relatively ductile metal, such as the 60 boxes used to cover the tubes in radio apparatus.

While we have shown our machine as adapted to trim boxes of square cross section and with rounded corners, it will be obvious that boxes of other cross sections, such as square, triangular, 65 rectangular or hexagonal, as well as oval or elliptical, may be trimmed with equal facility by providing mandrels and associated parts to fit the different boxes, and by providing cutters 30 of such outline as to maintain substantially uniform overlap with the die which fits the box to be trimmed.

Having thus described our invention and the advantages thereof, we do not wish to be limited to the details herein disclosed, otherwise than as 75 set forth in the claims, but what we claim is:

1. A machine for trimming boxes of non-circular cross section comprising a die closely fitting the interior of the box to be trimmed, a cutter co-acting with said die, said cutter and die being mounted to rotate on fixed parallel axes 5 and said cutter being shaped to maintain substantially uniform box-trimming overlap therewith, and means to cause said die to rotate through a definite number of complete revolutions for each revolution of said cutter, whereby 10 the same parts of said cutter and die coact during each revolution of said cutter.

2. A machine for trimming boxes of non-circular cross section comprising a mandrel and die mounted to rotate together on a fixed axis, said 15 die closely fitting the interior of the box to be trimmed, a cutter mounted to rotate about a fixed parallel axis and having a non-circular cutting edge complementary to the edge of said die, and means to rotate said cutter and said die and 20 mandrel in predetermined speed relation such that complementary parts of said cutter and die coact during every revolution of said cutter.

3. A machine for trimming boxes of non-circular cross section comprising a cutter and a die 25 rotatable about fixed parallel axes, a mandrel rotatable with said die, said die closely fitting the interior of the box to be trimmed, and means to give said die and mandrel two complete revolutions for each revolution of said cutter, whereby 30 the same parts of said cutter and die always coact to trim the box, and the cutting edge of said cutter being shaped to maintain substantially uniform box-trimming overlap with said die in 35 every cutting relation of said parts.

4. A machine for trimming boxes comprising means to give a box two successive revolutions, means to trim a continuous scrap ring from the open end of the box during the first revolution, and means rotatable with the box and effective 40 to cut said scrap ring into segmental fragments during the second revolution of the box.

5. A machine for trimming boxes comprising a rotatable mandrel and die to support the box, a rotating cutter coacting with said die to trim a 45 continuous scrap ring from the open end of the box as the mandrel and cutter rotate, and means rotatable with said die and mandrel and effective to cut said ring into segmental fragments on further rotation of said cutter, mandrel and die.

6. A machine for trimming boxes comprising means to give the box two successive revolutions, means to trim a scrap ring from the open end of the box during the first revolution, and means to 55 cut said scrap ring into segmental fragments during the second revolution, said latter means co-acting with a non-cutting surface of an element rotating with said scrap severing means.

7. A machine for trimming boxes of non-circular cross section comprising a cutter and a die 60 rotatable about fixed parallel axes, a mandrel rotatable with said die, said die and mandrel closely fitting the interior of the box to be trimmed, and means to give said die and mandrel two complete revolutions for each revolution of 65 said cutter, said box being trimmed during the first revolution of said die and mandrel, and means being provided to subdivide the scrap ring severed during the first revolution into a plurality of segmental fragments during the second 70 revolution of said die and mandrel.

8. A machine for trimming boxes of non-circular cross section comprising a box-supporting mandrel, means to give said mandrel two successive and complete revolutions only, means to trim 75

the box on said mandrel during the first revolution, and means to cut the severed scrap ring into segmental fragments during the second revolution.

5 9. A machine for trimming boxes of non-circular cross section comprising a box-supporting mandrel, means to give said mandrel two successive and complete revolutions, means to trim the box on said mandrel during the first revolution, means to cut the severed scrap ring into segmental fragments during the second revolution, and means to stop the machine on the completion of the second revolution.

10 10. A machine for trimming boxes of non-circular cross section comprising a box-supporting mandrel, means to give said mandrel two successive and complete revolutions only, means to trim the box on said mandrel during the first revolution, and means to cut the severed scrap ring into segmental fragments during the second revolution, said trimming means comprising a die fitting the interior of the box to be trimmed and a cutter having a non-circular cutting edge complementary to said die and maintaining substantially uniform box-trimming overlap therewith.

15 11. A machine for trimming boxes of non-circular cross section comprising a box-supporting mandrel, means to give said mandrel two successive and complete revolutions only, means to trim the box on said mandrel during the first revolution, and means to cut the severed scrap ring into segmental fragments during the second revolution, said trimming means comprising a die fitting the interior of the box to be trimmed and a cutter having a non-circular cutting edge complementary to said die and maintaining substantially uniform box-trimming overlap therewith.

12. A machine for trimming boxes of non-circular cross section comprising a mandrel, a die and a scrap cutter all mounted to rotate together about a fixed axis and said die closely fitting the interior of the box to be trimmed, a cutter mounted to rotate about a fixed parallel axis and having a non-circular cutting edge complementary to the edge of said die, and means to rotate said cutter and said die, mandrel and scrap cutter in predetermined speed relation, such that complementary parts of said cutter and die contact during every revolution of said cutter, and said cutter having an associated concentric element rotating therewith and coacting with said scrap cutter on every alternate revolution of said scrap cutter.

13. Apparatus to subdivide scrap rings trimmed from the open ends of metal boxes comprising a rotatable scrap cutter around which said ring is deposited as trimmed from the box, said cutter having circumferentially spaced cutting elements thereon, and a member rotating about an axis parallel to the axis of said scrap cutter and having a surface coacting with said cutting elements to cut the scrap ring into segmental fragments.

14. Apparatus to subdivide scrap rings trimmed from the open ends of non-circular metal boxes comprising a polyangular rotatable scrap cutter around which said ring is deposited as trimmed from said box, said cutter having cutting elements at a plurality of corners thereof, and a member rotating about an axis parallel to the axis of said scrap cutter and having a surface coacting with said cutting elements to cut the scrap ring into segmental fragments.
